UNITED STATES PATENT OFFICE

WILLIAM D. KYLE, OF MILWAUKEE, WISCONSIN, ASSIGNOR TO LINE MATERIAL COMPANY, OF SOUTH MILWAUKEE, WISCONSIN, A CORPORATION OF DELAWARE

ELECTRIC INSULATOR

Application filed September 30, 1929. Serial No. 396,247.

This invention relates to electric insulators and it is one of the objects of the present invention to provide an insulator having a terminal member formed therein. While the invention is of general application it is particularly applicable to insulators for dead ending insulated drop wires.

In electric wiring work it is customary for the wiring contractor to furnish the wire connections from the side of the building into the house. The power company extends a connection to the house from the pole carrying the power lines and at the same time it establishes a connection to the conductors located by the contractor on the side of the building and extending into the house. The incoming power wire is extended through an eye or perforation in an insulator or is wound around a groove in the insulator and the span is drawn tight. The end of the wire is bent back and twisted about the main part of the span wire to hold the same tight against the head of the insulator. A connection is then made between the span conductor and the wire extending along the side of the house. Heretofore, it has been necessary to solder the connection in order to secure a satisfactory joint having a low electrical resistance. It is a particular object of the present invention to provide an insulator adapted for dead ending a line wire, wherein the insulator is provided with a terminal whereby the desired connections may be made without the necessity of soldering the connection. While the insulator of the present invention is particularly useful for dead ending a line wire it is also capable of other uses and I do not wish to be limited to any particular use to which my insulator may be put.

In the embodiment of the invention which has been herein illustrated, I provide a unitary insulator having a body portion of frangible insulation. The insulator has an eye formed therein for receiving a line wire or it may have a peripheral groove around which the wire may be wound. The insulator has a terminal member, which may be of any preferred construction, embedded therein for establishing the desired connections. This construction not only obviates the necessity

for soldering the connection but also, since the terminal is rigidly fixed, it does not require taping to guard against the swinging of the connection into contact with the building or other grounded or live parts.

Another advantage of my invention is that it permits the power company to disconnect the line to the consumer outside of the building in a very efficient and simple manner.

The attainment of the above and further objects of the present invention will be apparent from the following specification taken in conjunction with the accompanying drawing forming a part thereof. In the drawing:

The single figure is a side view of an insulator and terminal constructed in accordance with my invention, said view showing the manner in which the insulator is adapted to be mounted.

Referring now more particularly to the figure, the insulator comprises a body portion 1 of suitable insulating material such as porcelain or the like, having a transverse line wire receiving opening 2 therein. The insulator also has an end groove 3, for receiving the end of a line or wire. The groove 3, extends across the top or outer end of the insulator and is rounded and relatively shallow with its well rounded edges merging into the well rounded edges of the opening 2. The insulator is likewise provided with a groove 4, formed therein for purposes well known in the art. A wood screw 5, of the self piercing type, is cemented into the base of the insulator and provides the means for mounting the insulator upon a wood support. The screw 5, which is made of metal, is adapted to be screwed into a wood support without previously drilling a hole therein. The shank portion of the screw is embedded in the body of the insulator and terminates at a distance from the opening 2. The screw may be embedded in the insulator during the process of molding the body thereof, as is well understood by those skilled in the art.

When the insulator is made of porcelain the screw 5 is embedded in a hole formed in the body of the insulator being held therein by a suitable porcelain cement, or by a lead filler. This is more clearly shown in my pending applica-

tion, Serial No. 376,202 filed July 5, 1929 to which reference may be had for a further description of the manner of embedding the screw within the insulator.

5 The insulator is provided in addition with a pair of projecting portions 37 and 37' which are formed integrally with the body of the insulator for protecting the terminal, said projecting portions being of the same material as and constituting a part of the insulator. A terminal 38 of suitable conducting material is embedded in the insulation and is provided with two holes 39 for receiving the bared ends of the conductors to be 10 connected and in addition is provided with a pair of set screws 39' for maintaining the ends of the conductors in place and in firm electric contact with the terminal. The projections 37 and 37' protect the terminal connections in that they tend to reduce the probability of accidentally touching the contact since they lie adjacent to a goodly portion of the contact terminal. It is understood that any other preferred form of terminal may be used 15 in connection with the insulator shown.

When used for dead ending a drop wire the insulator is mounted upon the side of the house by means of the screw 5, and the line wire is extended to the insulator with about 20 a foot of line extending beyond the insulator. The end of the wire is then passed through the eye or perforation 2, and the span is drawn tight. The end of the wire is then bent back and twisted about the main part of 25 the span wire to hold the same tight against the insulator and then the end of the wire is cleaned of its insulation and passed through one of the openings 39. The corresponding screw 39' is tightened against the wire thereby establishing a good electrical connection between the end of the wire and the terminal 38. The end of the wire which extends along 30 the side of the house is likewise cleaned of insulation and is passed through the other opening 39 and secured in firm electrical contact with the terminal 38 by means of the other screw 39'. This establishes a good electrical connection between the two conductors. This form of connection is highly 35 advantageous in that it eliminates the necessity of soldering. Insulators of the present type are generally mounted in a position such that soldering is extremely inconvenient and by overcoming the necessity for soldering the connection a good deal of time is saved.

In addition the mass of the connector is not suspended and free to swing. The connection is rigidly fixed to the insulator so that 40 it does not require taping to guard against the possible swinging together of loops or possible contact with the side of the building. Another advantage of the present construction lies in the fact that the power company 45 can disconnect the consumer outside of the

building in a very simple and efficient manner.

While I have herein shown and described a preferred embodiment of my invention it is to be understood that this invention is not limited to any specific construction herein shown, the same being merely illustrative of the invention. What I consider new and desire to secure by Letters Patent is:

As an article of manufacture, a combined 75 insulator and terminal comprising a unitary body of frangible insulation having a pre-formed curved configuration including an eye for holding a conductor in place thereon, said configuration being provided with well 80 rounded edges to prevent injury to a conductor held thereon, and a terminal member having one end extending into the insulator and being held in place thereby, said insulator including integrally formed portions 85 of insulation lying over and under the terminal for protecting the same.

In witness whereof, I hereunto subscribe my name this 12th day of Sept. 1929.
